ABSTRACT OF THE DISCLOSURE

An apparatus for programming a plurality of pressurized fluid actuated devices, such as fluid amplifiers, and including a series of perforate members having circular peripheries bearing against a rotatable drive shaft under force of gravity for rotation therewith, such members being readily manually lifted and rotated for varying or adjusting program timing.

BACKGROUND OF THE INVENTION

The invention relates to the field of pressurized fluid actuated apparatus, such as fluid amplifiers for example. It is well known, for example, to actuate a plurality of fluid amplifiers or similar devices in a predetermined sequence controlled by a perforate tape, card or disk passing between the input tubes of said amplifiers or fluid devices, and pressurized fluid output tubes disposed opposite said tubes and slightly spaced therefrom. The sequence of operation of said amplifiers or fluid devices depends on the relative locations of the perforations in said tape, card or disk, as is well known in the art. In order to vary or adjust the sequence of said amplifiers or devices, new perforate tapes, cards or disks are substituted for those previously employed. Such new perforate items have their perforations at locations thereon which differ from those on the previously employed perforate items, thereby varying the sequence in which jets of pressurized fluid are permitted to flow between said pressurized fluid output tubes and said input tubes of the fluid amplifiers or similar devices.

It is believed obvious that, if a fluid actuated device is actuated at an incorrect point in time in a period of a sequence of actuations of a plurality of such devices, controlled by a perforate tape, card or disk, it is expedient, in order to correct for such incorrect operation, to substitute a new tape, card or disk for the incorrectly perforated one rather than to change the locations of the input tube of the incorrectly actuated device and the associated output tube. Furthermore, if only small adjustments in the time sequence of said actuations are desired, it is similarly expedient to substitute new tapes, cards or disks for the incorrectly perforated ones. It is readily apparent, therefore, that it would be desirable to provide, where possible, adjustable timing apparatus for controlling the sequence of operation of fluid amplifiers or similar devices, such timing apparatus being minutely adjustable for minute corrections in said sequence of operations and selectively adjustable through a wide range for varying said sequence of operations. Accordingly, the present invention relates to timing apparatus for controlling repetitive sequences of operations of fluid amplifiers or similar fluid actuated devices, such apparatus being readily adjustable for either minutely regulating or for completely changing said sequences of operations.

SUMMARY OF THE INVENTION

In carrying out the invention there is provided a drive shaft mounted for driven rotation and supporting against

2

its periphery a plurality of spaced-apart cylindrical members normally engaged for rotation with said shaft but each manually readily removable from engagement therewith and independently rotatively movable, each such member embodying a fluid passage extending therethrough. The input tubes of fluid amplifiers or other pressurized fluid actuated devices can be disposed, for selective actuation thereof in the paths of travel of said passages during rotation of said members to receive, from one end of such passages, jets of fluid supplied to the opposite end of the passages during rotation of said shaft and members.

BRIEF DESCRIPTION OF THE DRAWINGS

FIG. 1 of the drawings comprises a side elevational view of one of the forms of the apparatus embodying the invention,

FIG. 2 is a top plan view of the apparatus of FIG. 1 taken along line 2—2 of FIG. 1,

FIG. 3 is a cross-sectional view taken along line 3—3 of FIG. 1,

FIG. 4 is a view schematically illustrating a modification of certain parts of the apparatus of the invention,

FIG. 5 is a view similar to FIG. 1 and illustrating an alternative form of apparatus embodying the invention,

FIG. 6 is a top plan view of a portion of the apparatus of FIG. 5 taken generally along line 6—6 of FIG. 5, and

FIG. 7 is a cross-sectional view taken along line 7—7 of FIG. 5.

Similar reference characters refer to similar parts in each of the figures of the drawings.

DESCRIPTION OF THE PREFERRED EMBODIMENTS

Referring first to FIGS. 1, 2 and 3, there is shown a longitudinal drive shaft 11 whose ends extend through suitable rotary bearings (not shown) provided in vertical end portions 12 and 13 of a suitable U-shaped support frame 14. Shaft 11 is retained within said bearings in any convenient manner such as, for example, by split rings 16 and 17 disposed in cooperative grooves provided in the outer periphery of shaft 11. For the purpose of providing driven rotation of shaft 11, a pulley 18 is provided on such shaft and is held thereon by a set screw 19 (FIG. 2) tightened against a flat portion 11a on shaft 11. The inner periphery of pulley 18 has a flat portion corresponding to said portion 11a to assure against rotational movement of the pulley upon the shaft. An idler shaft or roller 21 (FIGS. 2 and 3) also extends through suitable bearings (also not shown) provided in vertical end portions 12 and 13 of frame 14, such shaft being retained within such bearings in any convenient manner, such as by split rings 22 and 23 disposed in cooperative grooves provided in the outer periphery of shaft 21.

A series of spaced-apart cylindrical members, such as 26, having circular outer peripheries 26a are provided, such peripheries of the members bearing against the outer peripheries of shafts 11 and 21 under their own weight, that is, the circular peripheries of the members, such as 26, are engaged or urged downwardly against the outer peripheries of said shafts by the force of gravity. By such arrangement it will be apparent that any rotational motion imparted to shaft 11 by means of pulley 18 will, due to frictional engagement of said cylindrical members with said shaft, in turn be imparted to such members. It is pointed out, however, that if it is considered expedient or desirable to do so, the portions along the length of the outer periphery of shaft 11 with which the circular outer peripheries of the members, such as 26, are engaged, and, such outer peripheries of such members, may be provided with cooperative gear teeth to provide a more positive rotational driving engagement between said shaft and each of said members.

As shown in FIGS. 1, 2 and 3, each cylindrical member, such as 26, is provided with a fluid passage, such as 27, extending therethrough from one end or face of the respective cylindrical member through the other end or face thereof. Alternatively, and if found desirable or expedient, each member, such as 26, may be provided with a fluid passage such as 28 (FIG. 4) which extends through each respective member in a chordal or similar direction between first and second points on the outer periphery 26a of each respective member. Furthermore, if found necessary or expedient, the passages extending through said members, such as 26, may be in the form of slots such as designated by reference character 29 in FIG. 4 of the drawings. The passages such as 28 and 29 will be briefly further discussed hereinafter.

For the purpose of maintaining the members, such as 26, properly spaced along the length of shaft 11, there is provided a simple form of thrust bearings, such as bearings 31 (FIGS. 1 and 2) which may, for example, be ball bearings rotatively disposed in suitable sockets provided in support members such as 32. Support members 32 are, in turn, supported on a rod or bar 33 which is secured in any convenient manner to the top surface of the bottom of frame 14. One of said bearings is, as shown in FIGS. 1 and 2, disposed adjacent but preferably minutely spaced from each of the ends or faces of each cylindrical member, such as 26, and near those portions of such ends which are near the bottom of each respective member at any time during the rotation of such member. By such arrangement, if a cylindrical member such as 26 moves in either direction laterally along shaft 11, during rotation of such shaft and such member, the end of the respective member will contact the bearing, such as 31, adjacent that end and further lateral movement of the respective member will be prevented. The arrangement just discussed will be readily apparent from a brief glance at FIGS. 1 and 2 of the drawings.

A plurality of bearings, such as 36, and similar to bearings such as 31, are shown supported on the lower ends of support members 37 affixed to bars or rods 38 and 39 which are attached, in any convenient manner, to the top edges of end portions 12 and 13 of frame 14. Such bearings prevent, to the extent necessary, the toppling of each of the respective members, such as 26, if such members are of insufficient thickness, from end to end thereof, to rotate on shafts 13 and 21 in a vertically stable manner or attitude. It is pointed out at this time that, if bearings such as 36 are provided, the members, such as 26, can be substantially thinner, from end to end thereof, than illustrated in the drawings. Furthermore, if said cylindrical members are substantially thicker from end to end thereof, than illustrated, bearings, such as 36, need not necessarily be provided since such thicker members would inherently rotate on shafts 13 and 21 in a vertically stable attitude.

A pressurized fluid manifold 41 is supported in end portions 12 and 13 of frame 14, such manifold embodying a fluid passageway 42 to one end of which pressurized fluid at a constant pressure is supplied from any suitable source thereof, such source not being shown in the drawings for purposes of simplification thereof. The other end of passageway 42 in manifold 41 terminates near the end of the manifold.

There is associated with each cylindrical member, such as 26, a pressurized fluid conduit, spout or nozzle, such as 43, each embodying a fluid passage, such as 44. Each fluid passage such as 44 connects with said fluid passageway 42 in manifold 41. Thus pressurized fluid is constantly emitted in jets from the ends of conduits or nozzles, such as 43, each such jet being directed towards one end or face of the respectively associated cylindrical member, such as 26, and in the path of rotation of an entrance end of the fluid passage, such as 27, extending through the respective member and terminating at said one end or face of such member. Each conduit, spout or nozzle, such as 43, is affixed to manifold 41 so that the end of the respective noz-

zle is always adjacent the same point in the path of rotation or travel of the fluid passage in the respectively associated member, such as 26, and, therefore, the fluid jet issuing from the end of each respective nozzle always flows through the same path.

In employing the apparatus of the embodiment of the invention heretofore described, an input tube, such as 46, of each of a plurality of pressurized fluid actuated devices or fluid amplifiers which it is desired to actuate in accordance with a selected program therefor, is disposed and 10 suitably supported, in any convenient manner, at a selected point in the path of rotation or travel of the exit end of the fluid passage, such as 27, in a selectively associated one of the members, such as 26. Said point in said path of 15 rotation or travel is the point therein at which a jet of pressurized fluid will be issued from said exit end of said fluid passage and the input end of the respective input tube is located in said path of rotational travel so as to receive said fluid jet. In the arrangement shown in FIGS. 1, 2 20 and 3 of the drawings, said point is a point precisely opposite or in alignment with the end of each respective conduit or nozzle 43. If, for example, the passages extending through the members, such as 26, do not extend therethrough in the shortest direction from one of the faces of 25 each such member to the opposite face thereof, that is, if such passages extend through their respective members in diagonal, curved or crooked or otherwise devious paths, said selected points in the paths of rotation or travel of the exit ends of the passages will vary accordingly. This 30 will be readily apparent to those skilled in the art.

Assuming now that the input tubes of a plurality of pressurized fluid actuated devices are arranged as outlined above and as shown in FIGS. 1, 2 and 3 of the drawings, that pulley 18 is connected by a suitable drive belt to a 35 source of motive power suitable for rotationally driving shaft 11 and that manifold 41 is connected to said source of constant pressure pressurized fluid, it will be apparent that each of the members, such as 26, is being driven in synchronism with the rotation of shaft 11 and that jets of fluid are issuing from the ends of each of the fluid conduits or nozzles such as 43 to impinge upon the respective faces of members 26. As the passage, such as 27, in each 40 respective member, such as 26, passes a selected location, illustrated by the location of passage 27 shown in FIG. 3 of the drawings, a jet of pressurized fluid is supplied to the entrance end of such passage, and flows through the passage to exit from the exit end of the passage and enter the end of the respectively associated input tube, such as 46, and actuate the respective pressurized 45 fluid actuated device or fluid amplifier. It is apparent, therefore, that the sequence of actuation of said fluid devices depends on the rotational position of each of said members, such as 26, relative to the rotational positions of the others of such members. If it is desired to regulate, 50 adjust or vary said sequence of actuation of said fluid devices, it is only necessary to manually raise or lift one or more of the members, such as 26, out of contact or engagement with shaft 13, and preferably also out of engagement with shaft 21, and, thereby, temporarily interrupt further rotation of the raised or lifted member or members. 55 Each such member is, of course, thereafter again lowered into contact with said shafts. Additional or alternative adjustment, regulation, or variation of the programs for said fluid devices can be quickly made by lifting or raising one or more members, as described, and manually rotating each such raised member and then again lowering each member as discussed above. It will be apparent to those skilled in the art that the manual rotation or interruption of rotation of the members, such as 26, as described above, alters or varies the rotational positions of one or more passages 27 relative to the rotational 60 positions of such passages in others of said members, and that the sequence of actuation of said fluid devices, that is, the program therefore, may thus be varied, regulated 65 or adjusted.

Referring further to FIG. 4, there is shown a fluid conduit or nozzle 47 which may correspond to a nozzle or conduit such as 43. There is also shown the input tube 48 of a pressurized fluid actuated device or fluid amplifier, such input tube corresponding to an input tube such as 46. Such nozzle and tube are arranged so that a fluid jet issuing from nozzle 47 will be supplied to input tube 48 whenever passage 28 reaches its location shown in FIG. 4 during rotation of the respective member 26. Thus, as previously mentioned, the fluid passage extending through each respective cylindrical member, such as 26, may extend in a chordal direction through each respective member.

If the pressurized fluid actuated devices to be actuated by jets of pressurized fluid are of a type that are normally biased to a first condition and are actuated to a second condition when and only so long as jets of pressurized fluid are supplied thereto, each such device reverting to its biased or first condition upon termination of the respective jet supplied thereto, a slotted passage such as passage 29 (FIG. 4) previously discussed is employed for controlling the actuation of the devices.

Referring now to FIG. 5, 6 and 7, the alternative form of apparatus embodying the invention will be briefly discussed. Since the apparatus shown in such figures of the drawings is similar to an operates in substantially the same manner as the embodiment of the invention discussed heretofore in detail, only those features of the alternative embodiment which it is considered necessary to discuss to assure an understanding thereof will be treated in any detail.

A support frame 54 rotatably supports a drive shaft 51 and an axle 61. There are disposed upon axle 61 a plurality of idler rollers, such as 60 (FIG. 6), which are rotatable upon said axle and held against longitudinal movement along said axle by split rings such as 60a and 60b. A series of annular cylindrical members, such as 56, having circular inner peripheries, such as 56a, (FIG. 7) are disposed on drive shaft 51 and a respectively associated one of said rollers, such as 60, with said inner peripheries of the cylindrical members bearing, under the weight of such members, against the outer peripheries of shaft 51 and each respectively associated one of said rollers. That is to say, the inner peripheries of each of said annular cylindrical members are engaged or urged downwardly against the outer peripheries of shaft 51 and rollers, such as 60, under the force of gravity. Thus, such members in effect hang on said shaft and rollers. It is readily apparent, therefore, that said members frictionally engage shaft 51 in a rotationally driven relationship therewith. If considered expedient or desirable the outer periphery of shaft 51 and the inner peripheries of the annular cylindrical members, such as 56, can each be provided with cooperatively intermeshing gear teeth for a more positive driving relationship between said shaft and members.

Each of the members, such as 56, is provided with a fluid passage, such as 67, extending through each respective member from one end or face thereof through the other end or face of such member. As mentioned in conjunction with member 26 and as shown in FIG. 4, fluid passages such as 29, that is, in the form of a slot, can be provided in the members, such as 56, if necessary. Furthermore, chordal fluid passages, such as 28 (FIG. 4), can be provided in each of said annular cylindrical members if found desirable or expedient to do so. 65

In the embodiment of the invention as shown in FIGS. 5, 6 and 7, a pair of bearing support bars on rods 78 and 79 are secured to the end portions of frame 54 adjacent the lower portions thereof and in any convenient manner. Ball bearings, such as 76, are rotatably supported in bearing support members, such as 77, which are in turn secured to said support bars or rods 78 and 79. The ball bearings, such as 76, are disposed adjacent opposite faces or ends of each of the members, such as 56, and prevent 75

any tendency of such members to laterally pendulate during rotation of the members.

A support rod or bar 73 is attached to the top edges of the end portions of frame 54 at approximately the centers of such portions. Bearing support members, such as 72, 5 are attached to said rod and rotatively support ball bearings such as 71. First and second ones of each pair of such bearings are disposed adjacent opposite faces or ends of each of the members, such as 56. The ball bearings, 10 such as 71, are thrust bearings which prevent lateral movement of the annular cylindrical members, such as 56, longitudinally along shaft 51 and along the rollers, such as 60.

15 The remainder of the apparatus shown in FIGS. 5, 6
and 7 is substantially the same as that of FIGS. 1, 2 and
3, and no further detailed discussion of said apparatus is
considered necessary to an understanding of the structure
of the alternative embodiment of the invention. Furthermore,
20 the apparatus of such alternative embodiment operates and may be manually adjusted, regulated or varied
in a manner similar to that previously discussed and no
operational example of the alternative embodiment is
believed necessary. It is pointed out, however, that an
axle, such as 61, and associated rollers, such as 60, could
25 as well be employed in the embodiment of FIGS. 1, 2 and
3 in the place of idler shaft 21. Similarly, an idler shaft
such as 21 could as well be employed in the embodiment of
FIGS. 5, 6 and 7 in the place of said axle and rollers. As
also mentioned in conjunction with the first described
30 embodiment of the invention, the cylindrical members,
such as 56, used in the second embodiment of the invention
could be of greater or lesser thickness than that
illustrated, if such is found desirable or expedient. It is
further pointed out that a greater number of cylindrical
35 members than that shown or a lesser number of such
members, down to a minimum of two, could be employed
in either embodiment of the invention. Furthermore, said
members could be spaced closer or farther apart than
shown in the drawings, as is believed obvious.

40 Although there is herein shown and described only two forms of apparatus embodying the invention, it will be understood that such is not intended to be in any way limiting but that various changes and modifications may be made therein within the purview of the appended claims
45 without departing from the spirit and scope of the invention.

What is claimed is:

1. An adjustable timing apparatus for providing selectively variable programming of a plurality of pressurized fluid actuated devices each having a fluid input tube, such apparatus comprising, in combination,
    - (A) a plurality of cylindrical members each having a circular periphery and each embodying a fluid passage extending through the respective member,
    - (B) a drive shaft horizontally supported for driven rotation about its longitudinal axis;
    - (C) means including said drive shaft and at least one idler roller for supporting said cylindrical members in a spaced-apart relationship with each other, said circular peripheries of such members normally bearing against the periphery of said shaft under the force of gravity for driven rotation with the shaft, each such member being independently manually movably away from said periphery of said shaft to rotationally adjust the rotational position of such member in relationship to the respective rotational positions of each of the other such members; and
    - (D) means associated with each said cylindrical member for supplying a jet of pressurized fluid to one end of said fluid passage of the respective member each time such end of such passage passes a selected point in its path of travel during rotation of such member by said drive shaft, whereby said input tubes of said fluid actuated devices can be selectively disposed in the paths of travel of the other ends of said fluid

passages for receipt of said fluid jets supplied to said first ends of such passages to thereby actuate said devices in accordance with the program then selected therefor, and such program can be varied by rotationally adjusting the relative rotational positions of one or more of said cylindrical members in relationship to the then respective rotational positions of one or more of others of such members.

2. Apparatus in accordance with claim 1 and in which the circular peripheries of said cylindrical members normally bearing against the periphery of said drive shaft are the outer peripheries of such members.

3. Apparatus in accordance with claim 1 and in which said cylindrical members are annular and said circular peripheries thereof normally bearing against the periphery of said drive shaft are the inner peripheries of such members.

4. Timing apparatus for programming a plurality of pressurized fluid actuated devices each having at least one fluid input tube, such apparatus comprising, in combination,

- (A) a plurality of cylindrical members each having a circular periphery and each embodying a fluid passage extending through the respective member,
- (B) a drive shaft horizontally supported for driven rotation about its longitudinal axis;
- (C) means including said drive shaft for supporting said cylindrical members in a spaced-apart relationship with each other, said circular peripheries of such members being normally forced solely by their own weight against the periphery of said shaft for driven rotation therewith; and
- (D) means associated with each said cylindrical member for supplying a jet of pressurized fluid to one end of said fluid passage of the respective member each time such end of such passage passes a selected point

5

10

15

20

25

in its path of travel during rotation of the respective member by said shaft, whereby said input tubes of said fluid actuated devices can be selectively disposed in the paths of travel of the other ends of said fluid passages for receipt of said fluid jets supplied to said first ends of such passages to thereby actuate said devices in accordance with the program then selected therefor, and such program can be varied by manually lifting one or more of said cylindrical members from against said periphery of said shaft and rotationally adjusting the relative rotational positions of such members in relationship to the then respective rotational positions of one or more of others of such members.

5. Apparatus in accordance with claim 4 and in which the circular peripheries of said cylindrical members normally forced against the periphery of said drive shaft are the outer peripheries of such members.

6. Apparatus in accordance with claim 4 and in which said cylindrical members are annular and said circular peripheries thereof normally forced against the periphery of said drive shaft are the inner peripheries of such members.
